ABSTRACT

Triene hydrocarbons containing two conjugated double bonds, represented by the formula:

wherein R₁, R₂, R₃, R₄, R and R' may be hydrogen, alkyl or aryl radicals, and which may be prepared through a Diels-Alder reaction between a cyclopentadiene and (a) a dihalide-alkenyl compound, followed by dehydrohalogenation with basic agents, or (b) esters of fumaric or maleic acid, followed by reaction with a Grignard's reagent and then by dehydration of the alcohol, are disclosed.

3 Claims, No Drawings

POLYENE HYDROCARBONS AND PROCESS FOR
OBTAINING SAME

The present invention relates to new polyene hydrocarbons and to the process for obtaining same.

More particularly the present invention relates to triene hydrocarbons containing two conjugated double bonds and having the following general formula:

wherein R₁, R₂, R₃, R₄, R and R' may be hydrogen, alkyl or aryl radicals.

The above hydrocarbons are obtained by means of a Diels-Alder reaction between a substituted or unsubstituted cyclopentadiene and dihalide-alkenyl compounds, and then of a dehydrohalogenation by basic agents:

The polyene hydrocarbons according to the present invention are also obtained by means of a Diels-Alder reaction between a substituted or unsubstituted cyclopentadiene and esters of fumaric or maleic acid, by a following reaction with a Grignard reactant and then by dehydration of the alcohol:

In the above reaction schemes R, R₁, R₂, R₃, R₄, R' and R'' have the aforesaid meanings, and X is a halogen as Cl, Br or I. The reactions according to the process of the present invention are carried out at a temperature comprised in the range from -10° to 100° C and in the presence of a solvent which may be selected from esters as tetrahydrofuran, dioxane, ethyl ether, butyl ether and the like, or aromatic hydrocarbons as benzene, toluene, xylenes or mixtures of the cited solvents.

Typical unrestrictive examples of triene compounds according to the present invention are the following ones:

2-ethyliden-3-isopropyliden-norbor-5-ene

2-enethylen-3-butyliden-norbor-5-ene

2,3-diethyliden-norbor-5-ene

The invention is now illustrated by the following unrestrictive examples.

EXAMPLE I

In a vessel provided with a reflux condenser, a loading funnel and a stirrer, 2 moles of cyclopentadiene were added to 2 moles of a toluene suspension of dimethylfumarate, the adding being carried out drop by drop. The reaction was finished after 24 h, and the obtained product was distilled (0.2 mmHg) at 96°+98° C after the toluene solution had been washed by a saturated solution of NaHCO₃.

The product, dissolved into ethyl ether, was dropped into a solution of CH₃ MgI (8 moles). The adding having been finished, the obtained mixture was allowed to reflow under stirring for 24 hours, then the magnesium salt were hydrolyzed by a watery solution of CH₃COOH.

It was extracted by ether, the extract was washed by a solution of NaHCO₃ and the solvent was removed by distillation.

The resulting alcohol was purified by crystallizing it from pentane; it was dehydrated by dissolving into pyridine, and dropping 4 moles of SO₂ Cl₂ into the reaction solution, at 0° C. After about 60 minutes, the solution was returned to room temperature, then treated by a watery solution of CH₃COOH, extracted by ether, and the extract was washed by a solution of NaHCO₃.

A product was isolated by an isomerization employing trialkylamides of the phosphoric acid as catalysts (French Pat. 1,529,455) and then by a distillation, which product had MW = 174 and b.p. = 75+80° C/1 mmHg.

The gas-chromatographic retention time (on 3 m EAS column on 5 percent of 60-80 mesh firebrick) was 4 minutes 2 seconds at 150°-190° C.

The total yields were 25 percent. The spectroscopic investigations showed agreement with the compound I.

EXAMPLE II

An ether solution of 2,3-diacyetyl norbor-5-ene was slowly dropped into an ether suspension of AlH₄.

The obtained alcohol was dehydrated by SO₂ Cl₂ and pyridine at 0° C by working according to example I.

According to the above working procedure, a mixture of products was isolated, which were isomerized by means of catalysts of the type trialkylamides of phosphoric acid (F.P. 1,529,455); a product was separated by distillation; which product had M.W. = 146 and showed a good agreement to the compound IV.

What we claim is:

1. Polyene hydrocarbons containing two conjugated double bonds having the following general formula:

in which R₁, R₂, R₃, R₄, R and R' are hydrogen, alkyl or aryl radicals.

2. A process for preparing polyene hydrocarbons as claimed in claim 1 consisting in reacting a diene as

with a dihalide alkenyl as

10 wherein R₁, R₂, R₃, R₄, R and R' have the known meanings, and X is a halogen as Cl, Br, I.

3. A process for preparing polyene hydrocarbons as claimed in claim 1 in which said hydrocarbons are obtained by a Diels-Alder reaction between cyclopentadiene and an ester of the 15 fumaric or maleic acid, by a following reaction with a Grignard reactant and then by dehydrating the so obtained alcohol.

UNITED STATES PATENT OFFICE
CERTIFICATE OF CORRECTION

Patent No. 3,676,510 Dated July 11, 1972

Inventor(s) Sergio Arrighetti, et al

It is certified that error appears in the above-identified patent
and that said Letters Patent are hereby corrected as shown below:

Column 3, correct the first formula to read:

Signed and sealed this 19th day of February 1974.
